UNITED STATES PATENT OFFICE

135,098

DESIGN FOR A GEOGRAPHIC AMUSEMENT GAME DEVICE

Fred Scherbaun, Detroit, Mich.

Application December 24, 1941, Serial No. 104,825

Term of patent 3½ years

To all whom it may concern:

Be it known that I, Fred Scherbaun, a citizen of the United States, residing at 3429 Ludden Street, Detroit, in the county of Wayne and State of Michigan, have invented a new, original, and ornamental Design for a Geographic Amusement Game Device, of which the following is a specification, reference being had to the accompanying drawing, forming a part thereof.

Fig. 1 is a front elevational view of a geo-

graphic amusement game device, showing my new design; and

Fig. 2 is a front perspective view thereof with only a fragmentary section of the scroll border drawn in full lines.

I claim:

The ornamental design for a geographic amusement game device, as shown and described.

FRED SCHERBAUN.
